UNITED STATES PATENT OFFICE.

CHARLES BRUCE ARNOLD, OF GLENCOE, KENTUCKY.

HAND CORN-PLANTER.

SPECIFICATION forming part of Letters Patent No. 315,881, dated April 14, 1885.

Application filed July 3, 1884. (No model.)

To all whom it may concern:

Be it known that I, CHARLES B. ARNOLD, a citizen of the United States, residing at Glen-
5 coe, in the county of Gallatin and State of Ken-
tucky, have invented a new and useful Hand
Corn-Planter, of which the following is a spec-
ification, reference being had to the accom-
panying drawings.

My invention relates to hand corn-planters;
10 and it has for its object to provide a corn-planter
of the class referred to that shall possess su-
perior advantages in point of simplicity, cheap-
ness, durability, and general efficiency over
15 others of its class; and my invention consists
in the construction and novel arrangement of
parts, as will be hereinafter fully described, and
particularly pointed out in the claim.

In the drawings, Figure 1 is a view in per-
20 spective of my improved corn-planter, a por-
tion of the fabric that connects the legs to-
gether and also a portion of the fabric that
covers the seed-tubes being broken away. Fig.
2 is a vertical sectional view, and Fig. 3 is a
25 horizontal cross-section above the seed-slide.
Fig. 4 is a detail view of a modification of
the seed-slide. Fig. 5 is a detail view of the taper-
ing strips.

Referring by letter to the accompanying
drawings, A B designate the legs of the plan-
30 ter, which are provided with handles C C at
their upper ends and at their lower ends with
blades D D, having inturned flanges E E, by
which they are hinged or pivoted together in
35 such a manner as to be capable of being opened
and closed in the usual manner.

F is the box or hopper, which is rectangular
in form and is secured to the leg B. The hop-
per F is provided with a sliding lid, G, and
just above its bottom in its outer wall, H, it is
40 provided with a transverse opening, I, extend-
ing nearly across said wall. To the inner face
of said wall H, and projecting slightly below
the upper edge of the transverse opening I, is
45 a transverse wooden strip, J, which is secured
in place by two screws, K, passed through
washers and through holes in the wall H into
said strip J. The bottom of the hopper is of
wood. The leg B forms the front side of the
50 hopper and is provided with a transverse open-
ing, K'. Within the hopper, and secured to
the face of the leg B above the transverse open-
ing K' in such a manner as to project down-

and partially close said opening K', are sec-
tions L of rolled rubber or leather, which, when
the planter is in operation, rest upon the seed-
slide and rake the corn into the seed-tubes. 55
Guide-cleats M are provided at the ends of the
rolled rubber or leather sections, and are se-
cured to the leg B, there being but two of said
cleats. The leg B is provided on its inner face—
60 that is, the face opposite the hopper—with
four tapering strips, N N' N² N³, of wood, which
are securely nailed thereto, and extend from
the lower edge of the transverse opening K to
the lower end of the wooden portion of the leg 65
B. The two outer strips, N N², are widest at
their upper end and taper toward their lower
end, their outer edges being straight and flush
with the outer edges of the leg B. The two
inner strips, N' N³, are widest at their lower 70
ends. Their adjacent edges are straight and
the edges farthest apart are tapered. The low-
er ends of the intermediate strips, N' N³, are
beveled on both faces to form points thereon.
Between the upper ends of the outer and in- 75
termediate strips the leg B is gouged from the
transverse opening K downwardly for short
distances to form mouths for the three seed-
tubes O O' O², formed between the tapering
strips. The seed-tubes are formed by cover- 80
ing the tapering strips and the spaces between
them with a piece of fabric, P, of oil-cloth or
the like material. The fabric is secured in
place by tacks, and extends from the upper
ends of the strips to the commencement of the 85
bevels on the lower ends of the intermediate
strips. The upper connection between the legs
A and B is made by securing two slightly
downward-tapering pieces of oil-cloth or other
suitable material to the sides of the hopper by 90
screws, and below the hopper to the edges of
the legs, by tacks, in a firm manner. The seed-
slide Q is of double length—that is, it passes
entirely through the hopper, and projects
through the transverse opening in the hopper- 95
wall H. The free end of the seed-slide Q is
never drawn entirely within the hopper dur-
ing the operation of the planter. The seed-
slide Q is of copper or malleable cast-iron, pref-
erably, and is polished on its upper face to in- 100
sure easy and accurate working in its guides.
This slide has an offset or raised portion near
its rear end, as shown at R, and in front of this
raised portion R are three seed-openings, S S'

S^2 , arranged in a transverse line. These seed-openings cut slightly into the offset R, and the offset is beveled downward and forward to insure the entrance of the corn to seed-openings. 5 While the seed-openings are over the bottom of the hopper they form seed-cups; but when over the seed-tubes they form openings through which the corn drops into the seed-tubes. The middle seed-tube, O', is straight and discharges 10 at the middle of the bottom of the planter. The seed-tubes O and O² incline outwardly and discharge on opposite sides of the middle tube, O'. These seed-cups hold one grain of corn each. The seed-slide Q has an integral horizontal 15 stem, T, provided near its outer end with a vertical perforation, U. This stem T passes into a rectangular opening, V, in the leg A, directly opposite the transverse opening in the leg B, and the leg A is provided on its inner face 20 above and below the opening V with staples W W' W². A hook-rod, X, having the hook at its upper end, is passed down through the uppermost staple, W, through vertical perforation U in the stem T, and through the staples W' W², and forms the fastening for the seed-slide. A guide and stop-block, y, is secured to the leg B above the transverse opening K at the middle of the leg, and projects 25 down part way over the said opening K. This block serves as a guide for the seed-slide. 30 In the modification the seed-slide is cut off

a short distance in front of the seed-cups, and its forward edge is beveled downward and forward, as shown at a. Its side edges are provided with tongues, as shown at b, and the transverse opening I in the wall H of the hopper is omitted, and the bottom of the hopper is provided with grooves for the tongues b. In other respects the planter is constructed as hereinbefore described. 35

40 From the foregoing description, taken in connection with the drawings, the operation of the hand-planter will be readily understood without further explanation.

Having thus fully described my invention, 45 what I claim as new, and desire to secure by Letters Patent of the United States, is—

The combination, in a hand corn-planter, with the leg B, provided with the strips N N² at opposite sides on its inner face, tapering to 50 a point from above downward, of the intermediate strips, N' N², tapering from below upward, and the fabric P, for covering the strips to form the seed-tubes, as set forth.

In testimony that I claim the foregoing as my 55 own I have hereto affixed my signature in presence of two witnesses.

CHARLES BRUCE ARNOLD.

Witnesses:

JOHN WILLIAM WHITT,
ROD PERRY.
